UNITED STATES PATENT OFFICE.

FRIEDRICH AESCHEBACH, OF AARAU, SWITZERLAND.

MIXING-MACHINE.

938,201.

Specification of Letters Patent. Patented Oct. 26, 1909.

Application filed February 18, 1908. Serial No. 416,595.

To all whom it may concern:

Be it known that I, FRIEDRICH AESCHEBACH, a citizen of the Republic of Switzerland, residing at Thorfeldstrasse 942, Aarau, in Switzerland, have invented certain new and useful Improvements in or Relating to Mixing-Machines; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates to improvements in mixing machines in which the mixing tank is rotatable about its central axis and can be inclined about a horizontal axis at a right angle to the central axis.

The invention consists in construction, combination and arrangement of the parts as hereinafter described and claimed.

A construction according to this invention is illustrated by way of example in the accompanying drawing, in which:

Figure 1 is a side elevation, Fig. 2 a section on the line A—B of Fig. 1 and Fig. 3 a rear elevation.

The mixing tank 1 can be closed by a cover 2.

3 is the central axis of the mixing tank. To the mixing tank 1 is secured a bevel toothed rim 4 provided with a sleeve 5 supported in a bearing 6 on a bridge or bracket 7, so that the mixing tank is arranged freely suspended. The bridge or bracket 7 is provided at both ends with pins 8 which have a joint horizontal axis at a right angle to the central axis 3. The pins 8 are rotatably supported in bearings in the frame 9. To one pin 8 is secured an extension pin 10 which carries, on a sleeve 13, a fast pulley 11 and a loose pulley 12. Further, on the sleeve 13 is mounted a toothed wheel 14 which engages with a toothed wheel 15, the spindle 16 of which is supported in a bearing 17 secured to the bracket 7. To the spindle 16 is also secured a bevel wheel 18 engaging with the bevel rim 4. To the other pin 8 is secured a worm wheel 19 with which engages a worm 20 provided with a hand wheel 21.

In the sleeve 5 is loosely rotatable another sleeve 22 to which is secured a shaft 23 the central line of which corresponds with the axis of the mixing tank. On the shaft 23 is

mounted the mixing blade 24 arranged in the mixing tank 1. To the sleeve 5 is secured a toothed wheel 25 engaging with two smaller toothed wheels 26 which, in addition to two toothed wheels 27 mounted on the similar spindles 29, are arranged in a casing 28 secured to the bearing 6. The toothed wheels 27 engage with a toothed wheel 30 which is secured to the sleeve 22.

In working, the central axis 3 of the mixing tank 1 is arranged at an angle to the horizontal as shown in Fig. 1, which position makes it possible to heat or cool the mixing tank by placing a fire under it or by plunging the bottom portion of the same into hot or cold water. If the fast pulley 11 is driven, the toothed wheels 14 and 15 rotate, and therefore also the beveled wheels 18 and 4, so that the mixing tank rotates about its central axis 3. The rotation is transmitted by the sleeve 5, toothed wheels 25, 26, 27 and 30 to the sleeve 22, and thus to the shaft 23 and to the mixing blade 24 which rotates in the same direction as the mixing vessel. The direction of rotation of the mixing blade could also be in the opposite direction to that of the mixing vessel, if the driving gear is suitably arranged. If it is desired to empty the mixing vessel 1, it is rotated, by rotating the hand wheel 21, the worm 20 and the worm wheel 19, about the pins 8 in the direction of the arrow shown in Fig. 1, in such manner that its central axis 3 comes into the position shown in Fig. 1 and marked 3'.

Having now particularly described and ascertained the nature of my said invention, and in what manner the same is to be performed, I declare that what I claim is:

1. A mixing machine comprising a container having an opening in one end, a hollow bearing axle rigidly secured to the other end of the container, a rotatable support in which said axle is journaled, a rotatable spindle, a pinion fixed thereon, an annular rack on the closed end of the container in mesh with the pinion, a shaft in the axle, a stirrer in the container mounted on the shaft, and gearing connecting axle and shaft. 95

2. A mixing machine comprising a container closed at one end and open at the other, a hollow bearing axle centrally fixed to the closed end, a support in which the axle is journaled adapted to rotate on an axis at right angles to the longitudinal axis 110 of the axle, a spindle journaled in the support, a pinion keyed on the spindle, an an-

nular rack on the closed end of the container in mesh with the pinion, means to rotate the spindle, a sleeve journaled in the axle, gears on the sleeve and axle, gears connecting said 5 gears, a shaft fixed in the sleeve and a stirrer in the container fixed on the shaft.

In testimony that I claim the foregoing

as my invention, I have signed my name in presence of two subscribing witnesses.

FRIEDRICH AESCHBACH.
